METHOD OF SOAP-MAKING

Fredrik Teodor Palmqvist, Stockholm, Sweden, assignor to Aktiebolaget Separator, Stockholm, Sweden, a corporation of Sweden

Application December 6, 1952, Serial No. 324,585

4 Claims. (Cl. 260—418)

This invention relates to an improved and simplified process of soap-making.

Heretofore soap has generally been produced according to the batch or boiler method in which fat and fatty oils are saponified with caustic soda in large caldrons. By the saponification a homogeneous solution of soap in water is obtained from which the soap is subsequently precipitated by adding salt. This precipitation (the graining) results not only in soap but also in a spent lye made up of water, glycerine, alkali, salts, and impurities. The soap is separated from the lye by gravity or centrifugal separation. From the spent lye, glycerine is then obtained. The neat soap separated as described above is subjected to one or more fitting operations in which water and some salt and lye solution are added to the soap, whereupon the mixture is brought to boiling. This produces a mixture of niger and neat soap. The latter is separated from the niger by gravity or centrifugal separation, whereupon the neat soap is worked up to a marketable product.

The conventional method has several drawbacks. Thus, the total manufacturing time is at least eight days. During all this time the soap mass has a temperature between 85 and 100° C., resulting in color deterioration of the material. Further, the heat consumption is very high because heat must be supplied during the long processing time, among other things to compensate the losses of heat which are unavoidable in spite of the insulation of the tanks. The apparatus also requires considerable space owing to the large quantities of material being simultaneously processed. In other words, the capacity per unit of time is low. From the point of view of the capital invested, it is also a considerable disadvantage that large quantities of raw material are kept tied up in the manufacturing process for the considerable period of time mentioned.

It is true that a few continuous soap making processes reduce some of the above disadvantages, but the initial cost of the plants is often very high.

In the process of the present invention, which is applicable both to the conventional method (the batch method) and the continuous method, the disadvantages referred to have been eliminated.

According to the present invention, the graining is carried out with an aqueous solution of an electrolyte which consists wholly or in part of alkali-hydroxide having a strong graining effect. In this way, a mixture is obtained from which the neat soap may be easily separated from the spent lye, for example, by gravity or centrifugal separation.

Owing to the strong graining action of the electrolyte, a neat soap phase with low electrolyte content is obtained, as will be explained in more detail below. The electrolyte consisting substantially of alkali hydroxide must in some way be neutralized, as a strongly alkaline soap is usually not desirable because the alkali irritates the skin. In experiments to neutralize the alkali with fatty acid, difficulties were always encountered in that

2

the soap thickened considerably, because it was not possible to distribute the fatty acid evenly in the grained soap. Local portions of soap having a very high viscosity were formed, enclosing unsaponified fatty acid or acid soap. As a consequence, on being stored, such soap showed discolored local portions or rancidity spots.

The difficulty in the neutralizing has been solved, according to the characteristic feature of the invention, by neutralizing the alkali-hydroxide content with such an amount of bi-valent or poly-valent acids and/or acid alkali salts of such acids, for example, phosphoric acid, boric acid, silicic acid, carbonic acid, sulphuric acid, citric acid, oxalic acid, phthalic acid, etc., that the composition of the soap mass becomes such that the neat soap will be in phase equilibrium with niger, the neutralization being carried out with substantially no formation of free niger, that is, so that separation into neat-soap and niger is unnecessary. The acids form salts with the excess alkali of the soap. The characteristic feature of the salts is their low graining effect.

The neutralizing agents referred to are usually added in the form of water solutions but may also, if required, be added in the form of a finely ground powder.

According to still another feature of the invention, the neutralizing may be carried out with a water solution of one of the above acids and/or their acid alkali salts, in which solution fatty acids and/or sulphonic acids and/or easily saponified fat and/or colophony, etc., have been emulsified. It has been proved in practice that, by taking this step, the risk of forming a highly viscous soap is eliminated, because the electrolyte concentration around the soap formed becomes relatively high.

The invention may be best explained with reference to a McBain diagram for soap. The accompanying drawings show five diagrams, of which Fig. 1 is a McBain diagram for soap; Fig. 2 is an enlargement of part of the Fig. 1 diagram, illustrating examples of the practice of the invention; and Figs. 3, 4 and 5 are modifications of Fig. 2 illustrating other examples.

Referring to Fig. 1, the diagram there shown is for sodium soap of a pure fatty acid, i. e., lauric acid, at +90° C. On the diagram, the percentage of electrolyte (by weight), in this case sodium chloride, is marked on the abscissa, and the percentage of soap (also by weight) on the ordinate. The reading of the composition at a point of the diagram, point *a*, for example, is made by following the right-angle co-ordinates from the axes. Thus, the composition at point *a* is 2.0% sodium chloride, 41.0% sodium laurate (soap), and the balance up to 100% makes 57.0% water. On the diagram, the neat soap zone is marked A, the middle soap zone B, the niger zone C, the graining zone D, and the fitting zone E. The first three zones represent homogeneous phases, whereas the last two represent non-homogeneous phases (mixed phases) made up of two components; the graining zone corresponding to a mixture of neat soap and spent lye, and the fitting zone to a mixture of neat soap and niger. The other zones of the diagram are without interest in this connection and will not be further dealt with.

When making soap according to the conventional method, the fat is saponified with soda lye of such a concentration that the composition of the soap formed will lie within the area C, that is, in the niger zone (for example, point *a*). Sodium chloride or sodium chloride solution is then added to the niger, whereby the composition of the material passes over to the right into the graining area, for example, point *b* of zone D. As this zone represents a non-homogeneous phase, the material can be divided into two pure phases by separating, that

is, a neat soap phase represented by point *c* of zone A, and a spent lye phase of very low soap content, about 0.3 to 0.5%, and of high electrolyte content, about 14% (point *d* of zone D). This spent lye keeps dissolved in it glycerine which has been liberated from the fat during the saponification as well as part of the impurities of the fat. The lye is passed to the glycerine extraction plant. The soap produced cannot yet be worked into a marketable product because it is not what is termed "millable." The consistency is hard and the material is brittle, and the soap would not keep together on being stamped.

In order to obtain a millable soap, the grained neat soap must be "fitted," which means that its composition, by adding water and a weak electrolyte, is displaced downward obliquely to the left on the diagram, into zone E. This zone like the graining zone D represents a non-homogeneous phase, so that the mass separates into two pure phases, one phase of fitted neat soap corresponding to a point on the boundary line of the zone A, as well as a niger phase corresponding to a point on the boundary line to zone C. Owing to the high viscosity and low difference in specific gravity between neat soap and niger, a satisfactory separation of the former from the latter takes about 3 to 4 days. After the niger has been separated from the neat soap, the niger is subjected to boiling in order to extract its soap content. If required, the niger may first be purified, as it now contains some further impurities from the neat soap. After drying and milling, the fitted neat soap may now be pressed into pieces of soap.

Zone A of the saponification diagram (Fig. 1) was above stated to represent a homogeneous phase, the neat soap phase. As will have been understood from the foregoing, however, the soap has different qualities within this zone, depending upon what other zone it borders. Neat soap in phase-equilibrium with spent lye, that is, soap having a composition corresponding to a point on the boundary line of zone D, is characterized by high viscosity and cannot, as already pointed out, be stamped into pieces of soap after milling. On the other hand, neat soap in phase-equilibrium with niger, that is, soap having a composition corresponding to a point on the boundary line of zone E, has a soft consistency and can be easily worked. The explanation of this is that the soap in zone A is made up of liquid crystals, the surfaces of which are moistened by the mother lye from which they have been precipitated, that is, in the first case spent lye and in the second case niger. The spent lye with its low viscosity and high percentage of sodium chloride is an inferior lubricant, which, among other things, can be understood from the fact that it feels rough between one's fingers. This fact causes a great inner friction in the neat soap, that is, great friction between the soap crystals, and the material can flow only with difficulty. The niger, on the other hand, is viscous, feels slippery and gives low inner friction to the neat soap. A neat soap in phase-equilibrium with niger is therefore soft and flows relatively easily.

The importance of the mother lye with regard to the workability of the soap has hitherto not been fully clear. The invention is largely based on the facts stated above.

As will be seen from the diagram of Fig. 1, it is possible to move from one zone of the diagram to another by adding various agents, for example, water or electrolyte. Adding highly concentrated electrolyte normally results in a displacement to the right, though the effect of the various electrolytes in this respect is more or less pronounced. Thus, to obtain the same effect as with 1 part sodium chloride, it is necessary to add, for example, 0.87 part sodium hydroxide, 1.30 parts sodium acetate, 1.56 parts sodium nitrate, 1.84 parts sodium carbonate, 2.00 parts sodium sulphate, 3.00 parts sodium tetraborate, 2.34 parts tri-sodium phosphate, 2.34 parts sodium pyrophosphate, 2.8 to 3.7 parts sodium silicate (depending on the $\text{Na}_2\text{O}:\text{SiO}_2$ ratio) and about 6.7 parts potassium

silicate. It is said that the electrolytes have different strong graining actions because larger quantities are required of some of them than of others in order to transfer the niger phase (zone C) to the graining zone D. It will also be understood from the above that when an electrolyte with strong graining effect is used, the electrolyte percentage will be low in the neat soap phase and the spent lye, whereas it will be high in both phases when an electrolyte with mild graining action is used.

As will also be seen from the above figures, soda lye has the strongest graining effect of the electrolytes mentioned.

On the other hand, by the addition of a further electrolyte in the form of a water solution of bi-valent or poly-valent acid (or acid alkali salts thereof) to an alkali-hydroxide-containing neat soap, in the neutralization according to the present invention, the displacement occurs to the left instead of to the right in the diagram. In other words, the displacement will be into the fitting zone, if the starting material was a neat soap in phase-equilibrium with spent lye. Thus, to take an example, 1 mole phosphoric acid binds 3 moles sodium hydroxide with the graining coefficient 0.87 to a single mole tri-sodium phosphate with the graining coefficient 2.34. The neutralizing may be conducted so that the amount of niger formed becomes so small that separation into neat-soap and niger is not necessary, the form of the soap-mass at this stage allowing it to be directly worked in the usual way to a marketable product. The fitting stage is thus seemingly omitted, but nevertheless a soap is obtained with the characteristic malleable texture produced by the fitting process and necessary to get a ready-to-use soap of good quality.

The invention has been explained above with reference to a neat soap which has been grained out mainly with alkali hydroxide, and then transferred to a millable stage by wholly or partly neutralizing the alkali hydroxide with poly-valent acids or acid salts thereof, the mother lye between the soap crystals also being transferred in this way from spent lye to niger. The soap produced has thereby become millable. However, it may be pointed out that "grained neat soap" must also include soap which has already been subjected to the usual fitting but owing to subsequent temperature changes, or the like circumstances, has again assumed the character of a grained neat soap. (The McBain diagram has, consequently, a different appearance at different temperatures.) Such a soap can also to advantage be treated according to the present invention, provided that it has a certain remaining alkalinity.

The invention will now be explained in more detail with reference to the following examples, in which all statements concerning parts and percentages refer to weight.

Example 1

This example refers to a case in which neat-soap, made up of sodium laurate and grained mainly with alkali hydroxide, is transferred into a millable and stampable state by phosphoric acid.

639 parts of lauric acid triglyceride are saponified with 991 parts of 15% soda lye (the equivalent of 148.5 parts dry sodium hydroxide). This produces a niger holding 667 parts of soap (dry weight), that is, the soap percentage of the niger is 41%. The niger also contains free sodium hydroxide in an amount of 1.75% which, with regard to graining effect, corresponds to 2% sodium chloride. The composition of the niger thus answers to point *a* of the diagram, Fig. 1.

The niger is grained with 176 parts of 35% soda lye (61.6 parts dry NaOH) and 100 parts of 20% sodium chloride solution (20 parts dry NaCl).

The graining agent and the sodium hydroxide content of the niger gives a $\text{NaOH}:\text{NaCl}$ ratio corresponding to 4.5:1. By adding the graining agent, a displacement takes place on the diagram of Fig. 1 from point *a* to point *b* (35.0% soap and 6.5% electrolyte, calculated as NaCl).

5

which latter point is situated within the graining zone D near its boundary with the niger zone C.

When separating the grained soap from the lye (by gravity or centrifugal separation) a neat soap is obtained which contains 57.2% soap and 1.9% electrolyte, calculated as NaCl. The neat soap corresponds to point c of the diagram. The spent lye obtained by the separating has a composition corresponding to d of the diagram (0.5% soap and 13.7% electrolyte, calculated as NaCl).

The above neat soap has a content of free sodium hydroxide of 1.38%. According to the present invention, part of the free alkali is neutralized with 30% phosphoric acid. When adding 1.04 parts of phosphoric acid to 100 parts of neat soap a displacement takes place from point c of Fig. 2 (identical with point c of Fig. 1, Fig. 2 being an enlargement of part of the diagram of Fig. 1) to point e, in which the NaOH percentage has dropped to 0.99% by the addition of phosphoric acid. The point e, which is also located within the neat soap zone A, corresponds to 56.6% soap and 1.67% NaCl. By adding another 1.86 parts of phosphoric acid the content of free alkali of the neat soap is lowered to 0.31%, or to point f which is situated in the fitting zone E. This point corresponds to 55.6% soap and 1.28% NaCl.

Example 2

Starting from point c of Fig. 2, the free alkali of the neat soap is wholly neutralized with 50% NaH₂PO₄ (4.14 parts solution to 100 parts soap). A displacement then takes place to point g within the fitting zone E. Point g corresponds to 54.9% soap and 1.46% electrolyte, calculated as NaCl.

Example 3

This example shows how toilet soap grained out mainly with alkali hydroxide is made stampable by neutralizing with mono-sodium phosphate. The fat used in the manufacture was a mixture of tallow, bone-fat, palm oil, and cocoanut fat. By graining out the niger mainly with alkali hydroxide a neat soap was obtained, the composition of which answers to point h of the diagram of Fig. 3, or 71.2% soap and 0.52% electrolyte calculated as NaCl. The electrolyte is actually made up of 0.09% NaCl and 0.37% NaOH. On adding 1.10 parts of 30% NaH₂PO₄ to 100 parts of neat soap, the NaOH percentage is reduced to 0.15%, and the composition of the material passes to point i of the fitting zone E, which corresponds to 70.4% soap and 0.45% electrolyte calculated as NaCl.

Example 4

By adding another 0.75 part of 30% NaH₂PO₄ solution to the soap of Example 3, all free NaOH is neutralized and the composition passes to the point j which is also situated within the fitting zone E. The point j corresponds to a composition of 69.9% soap and 0.41% electrolyte calculated as NaCl.

Example 5

This example uses as starting material soap according to Example 3 which is neutralized with an emulsion of oleic acid in a 30% NaH₂PO₄ solution. The ratio between oleic acid and mono-sodium phosphate in the emulsion is 20:80, with regard to the neutralizing action of the oleic acid and the phosphate on the free NaOH content of the soap. To 100 parts of neat soap having a composition corresponding to point h of the diagram (Fig. 3) 1.19 parts of the above emulsion (0.31 part of oleic acid + 0.88 part of 30% NaH₂PO₄ solution) are added. This causes the composition of the neat soap to move to a point k, corresponding to 70.7% soap and 0.42% electrolyte calculated as NaCl. The NaOH percentage has thereby been lowered to 0.15%.

Example 6

By adding another 0.81 part of the emulsion specified in Example 5 to the partially neutralized soap obtained

6

according to the same example, a soap is produced having a composition which corresponds to point l of the diagram (Fig. 3), that is, with 70.35% soap and 0.35% electrolyte calculated as NaCl. All sodium hydroxide has been neutralized.

Example 7

This example refers to a case in which toilet soap made from the identical fat mixture mentioned in Example 4, is grained and then fitted mainly with alkali hydroxide, in order to obtain a quicker gravity separation or a higher throughput in a continuously operating plant, whereupon the alkaline neat soap is neutralized with an emulsion of oleic acid in mono-sodium phosphate solution according to Example 5, to render harmless the alkali of the soap. Referring to Fig. 4, the product obtained is neat soap of a composition corresponding to point m of the diagram, that is, 70.9% soap and 0.48% electrolyte calculated as NaCl. The electrolyte is actually made up of 0.33% NaOH and 0.10% NaCl. 1.25 parts of an emulsion containing 0.33 parts oleic acid and 0.92 part of 30% NaH₂PO₄ solution are added to 100 parts of this neat soap. In this way, a soap is produced having a composition which corresponds to point n in the diagram, that is, 70.4% soap and 0.37% electrolyte calculated as NaCl. The sodium hydroxide percentage has been lowered to 0.10%.

By means of the above process, marketable products can be obtained in a considerably reduced manufacturing time when using the batch method, or with a larger throughput rate of the plant when using continuous manufacturing methods. The time-consuming fitting operation may thus be avoided and one or more grainings mainly with alkali hydroxide may be substituted, depending upon how bright the color of the soap should be and to what degree it is desirable to recover the glycerine. When only one alkaline graining is made, the time of production is reduced from about 6 days to 2 days.

In continuous soap making in which centrifugal separators are used, for example, the manufacturing process is considerably simplified and the capacity of the plant increased when the present method is utilized. Thus, a bright soap may be made by two alkaline grainings, which means that the throughput rate of the separators can be increased to twice the rate when working according to the old method with normal graining and fitting.

By using mainly alkali hydroxide for graining, a considerably brighter soap is obtained than when an electrolyte of conventional composition is used.

When the neutralizing is effected with such acids, for example, phosphoric acid, boric acid, or silicic acid and/or their acid alkali salts which form surface-active salts with the alkali hydroxide, these salts will effect the crystal structure of the soap in that relatively small crystals are formed. The soap may therefore be worked more easily to the desired fine texture so that it can be more readily formed than soap having a coarse crystal structure.

When suitable acids or salts are chosen for the neutralization according to the present invention, further advantages may be gained. Thus, alkali phosphates, for example, improve the qualities of the soap in that, when using hard water, an extra consumption of soap is avoided because the lime salts dissolved in the water react with the phosphates and form calcium phosphates and not with alkali salts of fatty acids. That is, the formation of lime soap is avoided. Depending upon what phosphoric acid salts are used, all precipitation of lime may also be prevented by using, for example, tripolyphosphate or a polymetaphosphate. These salts are capable of forming water-soluble complex salts with those substances which render the water hard. When the neutralizing is made, for example, with phosphoric acid in combination with a polymeric alkali phosphate or with acid alkali salts of some polyphosphoric acid (for example, acid tripolyphosphate), a still better effect than with orthophosphate is obtained, because at the same time that the soap mass is neutralized

it becomes possible, to a certain degree, for the soap to form complexes with earth-alkali ions, for example, those rendering the water hard. Furthermore, some alkali phosphates and borates have a buffering action on soap dissolved in water and therefore counteract irritating action on the skin by the alkali content of the soap.

The present invention is further explained by means of the following examples:

Example 8

The alkali content of soap according to Example 3 is partly neutralized with CO_2 , which with water in the soap forms H_2CO_3 , which is a bi-valent acid. To 100 parts of neat soap with a composition according to point *h* in the diagram of Fig. 5 are added 1.3 parts of water and furthermore 0.12 parts of CO_2 by allowing carbon dioxide gas to bubble into the soap mass. In this way the composition of the neat soap is displaced to point *o* of Fig. 5. Said point answers to the following composition: 70.2% soap and 0.34% electrolyte, calculated as NaCl . After the treatment the NaOH content amounts to 0.15%.

Example 9

The sodium hydroxide content of soap according to Example 3 is completely neutralized with an emulsion of lauric acid in 12.5% NaH_2PO_4 solution. The ratio between the lauric acid and the mono-sodium phosphate is 50:50 as regards the neutralizing effect of the respective components on the content of free NaOH of the soap. To 100 parts of neat soap with a composition according to point *h* of Fig. 5 are added 3.15 parts of an emulsion consisting of 0.925 parts of lauric acid and 2.225 parts of mono-sodium phosphate solution. The composition of the neat soap is in this way displaced to the point *p* of Fig. 5. The composition in this point is 70.0% soap and 0.32% electrolyte, calculated as NaCl .

Example 10

Soap according to Example 3 is neutralized with an emulsion of rosin and cocoa nut fat in a 25% NaH_2PO_4 solution so as to reach a final alkalinity of 0.20% NaOH . The neutralizing effect of the oil phase in relation to that of the electrolyte phase of the emulsion is 20:80. To 100 parts of neat soap with a composition according to point *h* of Fig. 5 are added 1.04 parts of an emulsion consisting of 0.135 parts of rosin, 0.09 parts of cocoa nut fat and 0.815 parts of mono-sodium phosphate solution. After this addition the soap has a composition corresponding to point *r* of the diagram. The composition in this point is 70.7% soap, 0.44% electrolyte, calculated as NaCl , and 0.20% NaOH .

Example 11

Soap according to Example 3 is neutralized with an emulsion of dodecylbenzenesulphonic acid in 15% NaHSO_4 solution, so as to reach a final alkalinity of 0.15%

NaOH . The ratio between the dodecylbenzenesulphonic acid and the monosodiumsulphate is 60:40, as regards the neutralizing effect of the respective components on the content of free NaOH of the soap. To 100 parts of neat soap with a composition according to point *h* of Fig. 5 are added 2.84 parts of an emulsion consisting of 1.08 parts of dodecylbenzenesulphonic acid and 1.76 parts of 15% NaHSO_4 solution. The composition of the neat soap is in this way displaced to the point *s* of Fig. 5. The composition in this point is 70.35% soap, 0.41% electrolyte, calculated as NaCl , and 0.15% NaOH .

In the examples described above there are no statements about emulsifying and stabilizing agents for the emulsions used as neutralizing agents. To those skilled in the art it is obvious that such agents are advantageously used. As an emulsifying agent there can be added a minor quantity (about 0.1 to 2%) of a compound acting in an acid medium, such as sodium-dodecylbenzenesulphonate or dodecylbenzenesulphonic acid. If the latter is used, its neutralizing effect must be taken into consideration. The emulsion can be stabilized by means of a colloid, which can be effected for instance by bringing the silicic acid of water-glass with a high SiO_2 content to precipitate.

1 claim:

1. In the art of soap-making wherein soap is grained out with an aqueous solution of an electrolyte made up at least partly of alkali hydroxide, and is then separated as neat soap from the spent lye, the improvement which comprises neutralizing the alkali hydroxide content of the neat soap with an agent selected from the group consisting of bi-valent and poly-valent acids and the acid alkali salts thereof, said neutralizing agent being added in a quantity such as to produce a soap mass in which the neat soap is in phase equilibrium with niger, said neutralizing being carried out with substantially no formation of free niger.

2. The improvement according to claim 1, wherein the neutralizing is carried out with a water solution of said agent in which a substance selected from the group consisting of fatty acids, sulphonic acids, readily saponified fat and colophony has been emulsified.

3. The improvement according to claim 1, wherein said agent is one which forms a salt having a low graining effect.

4. The improvement according to claim 1, wherein said agent is one forming surface-active compounds with the alkali hydroxide.
